C. A. BALCH & A. F. FEVERGEON.

WINDOW PULLEY,

APPLICATION FILED FEB. 8, 1915.

1,205,424.

Patented Nov. 21, 1916.

UNITED STATES PATENT OFFICE.

CLIFFORD A. BALCH AND ARMAND F. FEVERGEON, OF PASADENA, CALIFORNIA.

WINDOW-PULLEY.

1,205,424.

Specification of Letters Patent. Patented Nov. 21, 1916.

Application filed February 8, 1915. Serial No. 6,963.

To all whom it may concern:

Be it known that we, CLIFFORD A. BALCH and ARMAND F. FEVERGEON, both citizens of the United States, residing at Pasadena, in the county of Los Angeles and State of California, have invented a new and useful Window-Pulley, of which the following is a specification.

An object of this invention is to provide superior means for supporting window cords.

Some of the points of superiority gained may be enumerated as follows:—neater finish of the window; ease of mounting the pulley in place; saving of labor of installing; simplicity and cheapness of construction; guarding against binding of the sash on the pulleys thereby allowing the sash to be fitted closer to the jambs; non-exposure 20 of the hardware, thereby avoiding expensive finish for the pulleys; avoidance of wearing the cord on the pulleys by any jumping of the cord into the space between the sash and the pulley flanges; insurance 25 against displacement of the cord from the pulley; reduction of the number of holes required in the frame from twenty holes in the installation of a double sash window with pulleys as heretofore constructed to 30 only four holes as required for installing such a window with these newly invented pulleys.

A further object is to make provision whereby the weights may be practically applied on one side of the window frame thereby allowing a narrow mullion between double hung windows.

The invention is regarded as pioneer in that we provide a pulley having a plurality 40 of wheels mounted on a foot adapted to rest on and to be attached to the end of the head jamb or lintel of a window.

Other features of a pioneer character may appear from the subjoined detail description, and it is understood that we do not limit the invention to the specific form shown but may vary the construction without departing from the broad spirit of the invention set forth in the appended claims.

50 The accompanying drawings illustrate the invention.

Figure 1 is a fragmental side elevation of a double window to which two forms of our newly invented window pulley are applied.

55 Parts are broken away for clearness of illus-

tration. Fig. 2 is a fragmental plan from line x^2 , Fig. 1. Fig. 3 is a fragmental elevation from the right of Figs. 1 and 2. Fig. 4 is an enlarged plan of a pulley constructed in accordance with the invention 60 showing the two-wheeled pulley intact and showing in section the additional two wheels for use in hanging a double window. Fig. 5 is an enlarged fragmental side elevation of a single window frame and double sash 65 therein with pulley mounted on the head jamb and connected with said sashes and their counterbalancing weights by the usual sash cords. Fig. 6 is a vertical section on line x^6 , Figs. 4, 5 and 7. Fig. 7 is a section 70 viewed from line x^7 , Figs. 6 and 8. Fig. 8 is an elevation of the pulley from the right of Figs. 5 and 7. Fig. 9 is a plan of the stamping from which the pulley frame is struck up.

The pulley frame for both forms of pulley shown in Figs. 1 and 2 is struck up from the stamping *a* shown in Fig. 9, said stamping comprising the foot 1 having a lip 2 and the point 3 bent in one direction therefrom, said foot being connected with the standards 4, each of which is provided with rear, top and side extensions 5, 6, 7. The stamping is struck up from dotted lines *b*, *c*, *d*, *e*, the lip 2 and point 3 being bent at said lines 85 *b* and *c* in one direction and the standards 4 being bent at the lines *d*, *e*, in the other direction. The extremities of the extensions 5, 6, 7 are curved away from the standards 4 to form the guides 8, 9, 10. Each of the standards is provided with a central aperture 11 to receive an axle 12 which may be a tube or solid rod capable of being fixed against endwise displacement, either by nuts or by riveting the ends of the axle.

The pulley wheels 13 may be of any suitable construction, either cast metal, stamped sheet metal or other material molded or stamped. In the form shown said wheels are of a well-known stamped construction having thimble skein 14, and the axle is shown as a short piece of rod inserted through said thimble skeins and the aperture 11, and secured in place by riveting the ends as at 15, 16.

For use as ordinary double sash pulleys in which two weights are provided at each side of the window frame as in Figs. 5 and 6 only two pulley wheels 13 will be applied, and this will be on the outside of the stand.

ards and inclosed within the curved guides 8, 9, 10. The standards are spaced apart sufficiently to accommodate between them on the same axle the two other pulleys 13' 5 which are placed side by side between said standards in the operation of assembling and the axle 12 is inserted through the four wheels and secured by riveting the ends as at 15, 16.

- 10 It is understood that in practice each axle will be provided with a head as at 15 before the assembling is effected and also that washers *w* may be employed between the wheels and the head formed at 15, 16, and 15 also between the wheels and the standards, and also to separate the wheels as in Fig. 4. Such changes, however, are within the skill of the constructor and are not deemed necessary for satisfactory operation; and consequently in most of the views the simplest form of assemblage has been shown.

In Figs. 5 and 6 a finishing thimble 17 is shown inserted in the cord passages 18 made in the lintel 19. Said thimble 17 may be 25 secured in place by punching out points 20 by means of a nail set.

At the rear of the foot there are provided holes 22 through which nails or screws may be driven to hold the foot firmly on the head 30 jamb and the lip 2 is provided with a hole 23 through which a nail or screw may be driven into the end of the lintel. Said lip is located near a vertical drawn from the axle 12 and the front and rear edges of the 35 standards are aslant as shown in Fig. 7 for strength combined with minimum weight and also for neatness of appearance, the rear edges 24 of said standards being aslant toward the apertures 11 and the forward edges 40 25 being aslant away from said apertures 11.

In practical application the ends of the 45 lintel 19 terminate at the outer face of the jambs 26 and the pulley for each side of the window frame is secured in place by simply bringing the foot 1 on top of the lintel, the lip 2 against the end of the lintel and then by the stroke of a hammer the point 3 is driven into the lintel. Thereupon the nails or screws 27 are driven through the holes 22 50 and a nail 28 is driven through the hole 23. Thus the pulley consisting either of the two-wheeled or the four-wheeled type is fixed in place at each side of the window frame, either double or single. In case a double 55 window is being fitted the workman may flatten out the lip 2, so that it will lie flat on the head jamb as shown in Fig. 1. It is understood, however, that the manufacturer may supply the trade with pulleys having 60 the lips 2 in a common plane with the foot 1, this form being intended for use between the double windows as shown at *f* in Fig. 1.

In mounting a double window the two wheel pulleys are placed at *f* in proper position to receive the cord led directly up from 65

the inner sides of the sashes of the two windows and the two pulley cords 29, 30 from the adjacent sides of the sashes 31, 32 are led over their respective pulleys and deflect- 70 ed, see Fig. 2, so that they will pass over the intermediate wheels 13' of the outer four-wheel pulleys and thence down for attachment to their respective weights, and the sash cords from the outer sides of the sashes are led up over the outer wheels 13 75 of the four-wheeled pulley inside the guides 8, 9, 10 and then down to their respective weights.

The cords 29 from both sides of the lower sash 31 are slidingly connected to one weight 33 and the cords 30 from both sides of the upper sash 32 are slidingly connected to the other weight 34.

Other methods of hanging the windows may be employed without departing from 85 the spirit of the invention.

The headed ends of the pulley axle hold the pulley wheels in place and said wheels and axle in combination with the standards and foot form a strong and rigid structure 90 made of a comparatively light sheet metal stamping.

The lip being bent down from the end of the foot, stiffens the foot against bending along its length and the standards prevent 95 bending in the other direction.

The apertures are located near that edge of the standard adjacent the lip at the end of the foot so that the pulleys mounted on an axle carried in said apertures overhang or 100 project beyond the line of the foot end thus to hold the sash cords free from the window frame.

We claim:

1. An overhead window pulley comprising 105 a foot to rest on the lintel, and standards bent from opposite edges of the foot and extending upward from said foot to form supports for the ends of the pulley axle, such axle supported by the standards and a plurality of wheels mounted on the axle.

2. In a window pulley, a foot to rest on the lintel of a window frame, standards bent from opposite edges of said foot and extending in one direction therefrom to support the pulley axle, and a lip bent from another edge of said foot and extending in the other direction therefrom to engage the end of the 115 lintel.

3. In a window pulley, a foot to rest on the lintel of a window frame, standards extending from the foot to support a pulley axle, and extensions of said standards bent away from the standards respectively to 120 form cord guides.

4. A pulley frame struck up from sheet metal and comprising a foot to rest on the lintel of a window frame, standards joined to said foot and provided with apertures to 130

- receive the pulley axle, and extensions from said standards to form guides around the pulley wheel.
5. A pulley frame struck up from sheet metal comprising a foot, standards bent up from said foot in one direction, and a lip bent from said foot in the other direction between said standards, said standards being provided with apertures for the pulley axle.
- 10 6. A pulley comprising a foot, a lip bent down from said foot, standards bent up from said foot and provided with apertures for a pulley axle, said apertures being located at the edges of the standards nearest the lip, and pulley wheels mounted on said axle to project beyond the line of said edges, the other edges being widely separated from said apertures.
7. A window pulley comprising a foot, 20 standards extending up from said foot and provided with apertures, a pulley axle extending through said apertures, pulley wheels mounted on said pulley axle outside of said standards, and pulley wheels mounted on said axle between said standards.
- 25 8. A window pulley comprising a foot, standards extending up from said foot and provided with apertures, a pulley axle extending through said apertures, pulley wheels mounted on said pulley axle outside of said standards, and pulley wheels mounted on said axle between said standards, said pulleys being mounted near one end of the foot to project beyond the same.
- 30 35 9. A window pulley comprising a foot, a lip bent down from one end thereof, standards extending up from said foot and provided with apertures, a pulley axle extending through said apertures, pulley wheels mounted on said pulley axle outside of said standards, and pulley wheels mounted on said axle between said standards.
- 40 10. A window pulley comprising a foot, a lip bent down from one end thereof, stand-
- ards extending up from said foot and provided with apertures, a pulley axle extending through said apertures, pulley wheels mounted on said standards, and pulley wheels mounted on said axle between said standards, said pulley wheels being mounted near one end of the foot to project beyond the same.
11. A pulley comprising a foot; two standards bent up from said foot and provided with apertures; pulley wheels outside the standards and an axle extending through said apertures and pulley wheels and provided with heads to retain the pulley wheels.
12. An overhead window pulley comprising a foot, terminating at opposite edges in standards extending from one side thereof, an axle carried by the standards, and pulleys on said axle outside said standards.
13. An overhead window pulley comprising a foot, terminating at opposite edges in standards extending from one side thereof, an axle carried by the standards, pulleys on said axle outside said standards and pulleys on said axle between the standards.
14. A pulley frame constructed of a sheet metal blank stamped to form a foot, two standards and a lip, said lip being between said standards; said standards being bent up from opposite edges of said foot in one direction and said lip being bent from said foot in the other direction, said standards being provided with apertures for an axle, and pulley wheels on the axle outside said standards.
- In testimony whereof, we have hereunto set our hands at Los Angeles, California, this 28th day of January, 1915.
